UNITED STATES PATENT OFFICE.

SYDNEY HERBERT RUDDLE AND EDGAR CHURCHILL DAVIDSON, OF BRISBANE,
QUEENSLAND, AUSTRALIA.

DOUBLE-ACTING INTERNAL-COMBUSTION ENGINE.

1,303,598.

Specification of Letters Patent.

Patented May 13, 1919.

Application filed August 1, 1917. Serial No. 183,885.

To all whom it may concern:

Be it known that we, SYDNEY HERBERT RUDDLE and EDGAR CHURCHILL DAVIDSON, subjects of the King of Great Britain, residing at Brisbane, Queensland, Australia, have invented new and useful Improvements in Double - Acting Internal - Combustion Engines, of which the following is a specification.

10 This invention relates to improved double acting internal combustion engines wherein we are able to obtain, among other things, increased power as compared with other engines of equal size and weight, as well as compactness.

In carrying out our invention we provide one or more pairs of cylinders although we prefer that there be two, or a multiple of two, cylinders. Of each pair 20 of cylinders, which are arranged tandemwise, one cylinder has a greater diameter than the other. These cylinders contain a pair of pistons coupled or jointed together and arranged to drive a crank on a crank shaft. The smaller piston is in the form 25 of a trunk and within it projects a plug or fixed piston, if it may be so called, rigidly carried by the casing or as desired, so that an inner chamber is formed within 30 the piston and above the fixed piston wherein an explosion may take place, the usual explosion chamber being also provided between the end of the smaller piston and the end of the cylinder. The usual deflectors 35 are provided on the smaller piston and the fixed piston. Ignition is caused in the outer chamber by an ignition spark and in the inner chamber by a hot tube fitted in the upper end of the smaller piston, or by an 40 ignition spark. In this latter case an ignition plug would be fitted at the proper point in the cylinder, and an opening is formed through the smaller piston. In order to prevent leakage, one of the piston rings is 45 of extra width and the opening passes through same, the ring being prevented from moving at this point by a nipple preferably of two diameters screwed into the piston and ring.

50 The larger piston acts as a fuel compressor receiving the fuel from the carbureter through an inlet chamber and delivering it into a receiver, inlet and outlet valves being provided. We prefer that there should 55 be, for engines of ordinary horse power, two

pairs of cylinders arranged side by side, a common inlet chamber and receiver being provided for both pairs.

Inlet and exhaust ports leading to and from each explosion chamber are provided, 60 there being also ports in the smaller piston.

The usual water jackets are provided around the cylinders, exhaust passages, etc., and a water jacket is also provided in the 65 fixed piston.

Other details of carrying out our invention and which do not affect the essence thereof may be varied as required.

In order that our invention may be better understood we will now describe same more 70 fully with the aid of the accompanying drawings, in which—

Figure 1 is a part sectional part side elevation thereof.

Fig. 2 is an end sectional elevation.

Fig. 3 is a sectional plan of the cylinder casting,

Fig. 4 is a sectional elevation of the regulator in the container.

Fig. 5 is a plan of same,

Figs. 6, 7, 8 and 9 are detail views of the piston packing rings.

Figs. 10 and 11 are details of the clamping ring.

In carrying out our invention we have 85 one or more pairs of cylinders A, A', arranged tandemwise, and provided with the usual water jackets A² or other means for cooling; we prefer that there should be two or a multiple of two cylinders A, A'. Of 90 each pair of cylinders, one cylinder A has a lesser diameter than the other A'. These cylinders A, A' are bolted or otherwise secured on or to the crank case B. Between the pairs of tandem cylinders A, A', or 95 where convenient, is placed a receiver or container C. In some cases we may provide in this receiver or container C means whereby the area may be reduced or increased at will so that the degree of compression may 100 be varied as desired. This object is attained by means of a tube C' within which is a piston C² capable of being adjusted as to position by the screw C'.

Conveniently placed is the inlet D to 105 which is secured the carbureter (not shown). Passages D' lead from the inlet D to the cylinders A' and also from the cylinders A' to the receiver or container C, non-return valves D² being provided in such passages. 110

D. Inlet ports E lead from the receiver or container C to the cylinders A. Exhaust ports and passages F are also provided in and from the cylinders A. A single exhaust port and passages may be arranged if desired.

The cylinders A, A' contain a pair of pistons G G' coupled or joined together. The smaller piston G is in the form of a trunk and within it projects a plug or fixed piston G³, if it may be so called, rigidly carried by the casing, or as desired, such as by the bracket G⁴, or clamp G⁵ (Figs. 10 and 11). Inlet ports G⁶ and exhaust ports G⁷ are provided in the trunks of the pistons G. A water chamber G⁸ is formed in the fixed piston G³.

Explosion chambers H, H' are formed between the ends of the cylinders A and the pistons G and also between the inner sides of the pistons G and the fixed piston G³.

Ignition plugs J J' are provided in the cylinders A and ignition ports J² are provided in the pistons G. These ignition ports J² are formed by means of a nipple J³ of larger and smaller diameter screwed or otherwise secured in the piston A and passing through one of the packing rings J⁴ of the piston A which ring J⁴ may be broader than the others. We may in some cases provide passages (not shown) leading from the pockets around the terminals of the sparking plugs to the exhaust passage F, or as desired. Further we may in some cases provide a hot tube at J⁵ in the end of the piston G in lieu of the ignition plug J' in which case the corresponding ignition ports J² would be dispensed with.

Deflectors K are provided on the pistons G and fixed pistons G³ to deflect the incoming charge from the exhaust ports F.

The shaft L, which runs in bearings L', in the crank case B, has two cranks L² coupled to the pistons G' G² by the connecting rods L³. The crank L² of one pair of pistons G G' is set in opposition to that of the other.

The fly wheel is shown at M.

We may vary the constructional details of engines constructed according to our invention without interfering with the essence thereof. Certain details common to all internal combustion engines, and which do not form part of our invention although necessary for the proper working of the engine, such as pipes for supplying water to, or taking it from the jackets G⁸ A², lubricators, magneto or other means for ignition, etc., are not shown in the drawings.

The working of the engine is as follows:—

60 The fuel and air is regulated through the carbureter (not shown) connected up to the inlet D, whence it is drawn in by one of the pistons G' through the non-return valve and passage D' and forced through the upper 65 non-return valve D² to the receiver or con-

tainer C while another charge is being drawn in behind the other piston G' in the other cylinder A' during this return stroke to be delivered also to the receiver or container, C, on the next stroke. The degree of compression in the receiver or container C is regulated by adjusting the height of the piston C² by means of the screws C³. Meantime part of the first charge in the receiver or container C has been delivered through the inlet passage and ports E to, say, chamber H of the right hand cylinder A, while the rest of the charge has been delivered by the passage and ports E to chamber H' of the left hand cylinder A. These charges are compressed and fired simultaneously. Now, just before these charges are fired, two other charges from the receiver or container C are delivered, one to chamber H' of the right hand cylinder, and one to chamber H of the left hand cylinder. These charges are also compressed and fired simultaneously. At a suitable position in each stroke the burnt gases are allowed to escape (the exhaust ports being opened before the inlet ports) and fresh charges are admitted to the chambers above-mentioned. During each stroke two explosions occur together, one in each cylinder. Also every stroke of the piston, both upward and downward, is a working stroke.

Having now fully described and ascertained our said invention and the manner in which it is to be performed, we declare that what we claim is:—

1. In an improved double acting internal combustion engine, two, or a multiple of two, pairs of cylinders, said pairs of cylinders being of smaller and larger diameters, and arranged tandemwise, the smaller cylinders each having a closed end, a pair of pistons of smaller and larger diameters, working in unison within each of said cylinders, fixed pistons rigidly carried and projecting into said smaller pistons, compression and explosion chambers between the closed ends of the smaller cylinders and said smaller pistons and between said smaller pistons and said fixed pistons, the pistons in one of each two pairs of cylinders being arranged to work in opposition to those in the other, a crank shaft having cranks connected to said pistons by connecting rods, as and for the purposes herein set forth and as illustrated in the accompanying drawings. 115

2. In an improved double acting internal combustion engine, two, or a multiple of two, pairs of cylinders, said pairs of cylinders being of smaller and larger diameters, and arranged tandemwise, the smaller cylinders each having a closed end, a pair of pistons of smaller and larger diameters working in unison within each of said cylinders, trunks connecting said smaller and larger pistons, fixed pistons rigidly carried 120

and projecting into said smaller pistons, compression and explosion chambers between the closed ends of the smaller cylinders and said smaller pistons and between 5 said pistons and said fixed pistons, the pistons in one of each two pairs of cylinders being arranged to work in opposition to those in the other, a crank shaft having cranks connected to said pistons, a receiver, 10 fuel and air inlet passages to said receiver, inlet and exhaust passages and ports to and from the explosion chambers, inlet and exhaust ports in said trunks, ignition ports in said cylinders and in said smaller pistons 15 and means for ignition, as and for the purposes herein set forth and as illustrated in the accompanying drawings.

3. In an improved double acting internal combustion engine, an ignition port in a piston 20 in the cylinder of said engine, said port consisting of a nipple screwed through said piston and passing through a widened packing ring in said piston, as and for the purposes herein set forth and as illustrated in 25 the accompanying drawings.

4. In an internal combustion engine, a pair of cylinders, said pair of cylinders being of larger and smaller diameters and arranged tandem wise, the smaller cylinder 30 having a closed end, a pair of pistons of

smaller and larger diameters working in unison within said cylinders, a fixed piston within said smaller piston, compression and explosion chambers between said cylinder end and said piston, and between said piston 35 and said fixed piston, ignition means for said chambers, a compression chamber arranged between the larger piston and a wall of the cylinder, a receiver, means for conveying an explosive mixture to the last 40 named compression chamber and for conveying the mixture from said compression chamber to the receiver, a passage connecting the receiver with the smaller cylinder for conveying explosive mixture from the 45 receiver to the smaller cylinder, and a port in the smaller piston adapted to register with said passage for admitting explosive mixture to the compression and explosion chamber formed between the small piston 50 and fixed piston.

In testimony whereof we have signed our names to this specification in the presence of two subscribing witnesses.

SYDNEY HERBERT RUDDLE.
EDGAR CHURCHILL DAVIDSON.
